Des. 228,109
Patented Aug. 14, 1973

228,109

ADJUSTABLE RECORD HOLDER

Matthew B. Woods, Madley Road,
Lebanon, Conn. 06249

Filed Feb. 10, 1972, Ser. No. 225,372

Term of patent 14 years

Int. Cl. D6—04

U.S. Cl. D6—185

FIG. 1

FIG. 2

FIG. 3

FIG. 4

FIG. 5

FIG. 6

FIG. 7

FIG. 1 is a perspective view of an adjustable record holder showing my new design;

FIG. 2 is a top plan view thereof;

FIG. 3 is a front elevational view;

FIG. 4 is a rear elevational view;

FIG. 5 is a left end elevational view;

FIG. 6 is a right end elevational view; and

FIG. 7 is a bottom plan view thereof.

I claim:

The ornamental design for an adjustable record holder, as shown and described.
